UNITED STATES PATENT OFFICE.

EUGENE HAGGERTY, OF CLIFTON SPRINGS, NEW YORK, ASSIGNOR OF ONE-HALF TO
EDMUND F. NEEDHAM, OF PHELPS, NEW YORK.

GRAIN-DRILL.

1,370,108.

Specification of Letters Patent.

Patented Mar. 1, 1921.

Application filed May 4, 1920. Serial No. 378,839.

To all whom it may concern:

Be it known that I, EUGENE HAGGERTY, a citizen of the United States, residing at Clifton Springs, in the county of Ontario 5 and State of New York, have invented a new and useful Grain-Drill, of which the following is a specification.

It is the object of this invention to provide novel means whereby the shoe of a 10 grain drill may be raised either by power derived from the ground wheel, or by hand, and the invention aims particularly to improve the mechanism whereby the shoe is raised by the action of the ground wheel, 15 and to provide means whereby each of the raising instrumentalities may operate without interfering with the other.

The invention aims to improve generally 20 and to enhance the utility of devices of that type to which the invention appertains, and, within the scope of what is claimed, a mechanic may work changes, without departing from the spirit of the invention.

In the drawings:—Figure 1 shows in side 25 elevation, a device constructed in accordance with the invention, parts appearing in section; Fig. 2 is a top plan wherein parts are broken away; and Fig. 3 is a sectional detail disclosing sundry elements which are 30 located on the axle.

The device forming the subject matter of this application may form part of grain drills of widely different sorts, but in the drawings, the numeral 1 denotes a frame 35 having bearings 20 wherein an axle 2 is journaled, the axle carrying ground wheels 3, as usual. A planter shoe 4 is shown and is suspended at 5 from the frame 1 for vertical swinging movement toward and away 40 from the surface of the ground. A shaft 6 is journaled in bearings 60 on the frame 1. The shaft 6 is supplied with an arm 7 connected by any suitable means 8 with the shoe 4, the construction being such that 45 when the shaft 6 is rotated, the shoe 4 will be raised, all of the foregoing being more or less common.

The invention contemplates the provision 50 of means whereby the shaft 6 may be rotated either by the ground wheel 3, or by hand. Two different but coöoperating means are provided, therefore, for raising and lowering the shoe 4 by way of the shaft 6.

Considering, first, the wheel-actuated 55 means for operating the shaft 6, it will be

observed that a bracket 9 is attached to one side portion of the frame 1, by means of one of the bearings 20, if desired, as shown in Fig. 3. The bracket 9 is supplied with inwardly projecting arms 10 and 11. One end 60 of a lever 12 is pivoted at 14 to the arm 10, the other end 15 of the lever sliding on the arm 11. Intermediate its ends, the lever 12 is provided with an eye 16 having lugs 17 coöperating with the flange 19 of a sleeve 65 18 rotatable within the eye 16 and splined at 21 to the axle 2 to rotate therewith and to slide therealong.

A pinion 22 is rotatable on the axle 2 and is held against sliding movement longitudinally of the axle by a set collar 23 and a shoulder 24 on the axle. There is a projection 26 on one end of the hub of the pinion 22, the projection being adapted to coöperate with a projection 25 on the end of the 75 sleeve 18, the sleeve and the projections constituting, in effect, a clutch whereby the pinion 22 may be connected to the axle 2, to rotate therewith.

A cam or actuating member 27 is pivoted 80 at 28, intermediate its ends, to the arm 11 of the bracket 9 and bears at one end upon the end 15 of the lever 12. A retractile spring 29 is connected at its ends to the arm 11 of the bracket 9 and to the cam 27 at one side 85 of the pivotal mounting 28 of the cam. An operating element 30 is pivoted to the cam 27 and may be in the form of a rod. A compression spring 100 is interposed between the bracket 9 and the sleeve 18 and constitutes means for advancing the sleeve 18 so 90 that the projection 25 on the sleeve will lie in the path of the projection 26 on the pinion 22.

The numeral 31 denotes a loop-shaped 95 rack bar supported on the pinion 22 and provided on its lower edge with a rack 32 coacting with the pinion 22. The rack bar 31 has an extension 33 provided with a slot 34 receiving a pivot element 35 on an arm 100 36 projecting from the shaft 6.

A lever 37 is fulcrumed at 38, intermediate its ends, on the frame 1 and is pivoted at 39 to a link 40 having a slot 41 receiving a pivot element 42 on an arm 43 projecting 105 from the shaft. There is a stop 44 on the frame, adapted to coact with the upper end of the lever 37, under conditions to be pointed out hereinafter. An operating member 45 is connected to the lower end of 110

the lever 37. A link 46 is pivoted at 47 to the lower portion of the rack bar 31 and is provided with a slot 48 receiving a projection 49 on the lever 37. The rack bar 31 5 has a side projection 50 adapted to coöperate with the cam or actuating member 27.

The foregoing concludes the description 10 of the means whereby the shaft 6 may be operated from the wheel 4, and before taking up the description of the means whereby by the shaft 6 may be actuated by an operator, the way in which the shaft 6 is controlled from the wheel 3, will be explained.

Supposing that the parts 12, 27 and 18 15 are arranged as shown in Fig. 2, it will be understood that when the axle 2 is rotated by the ground wheel 3, the sleeve 18 will be rotated also, the projection 25 on the sleeve coacting with the projection 26 on the hub 20 of the pinion 22, to impart rotation to the pinion. When the pinion 22 is rotated, the pinion will move the rack bar 31 in the direction of the arrow A in Fig. 1, and when the rack bar moves as aforesaid, the pivot element 35 will arrive at the end of the slot 34 25 in the extension 33 of the rack bar, rotation being imparted to the shaft 6 by way of the arm 36. The arm 7 on the shaft 6, co-operating with the mechanism shown at 8, 30 will swing the shoe 4 upwardly on its pivotal mounting 5. When the rack bar 31 is moved in the direction of the arrow A, as aforesaid, the projection 50 on the rack bar engages the cam 27 and tilts the cam on its 35 pivot 28, the cam coöperating with the end 15 of the lever 12 to swing the lever on its fulcrum 14 and to slide the sleeve 18 on the shaft 12 until the projection 25 on the sleeve no longer is in the path of the projection 26 40 on the hub of the pinion 22. The axle 2 may now continue to rotate with the ground wheel 3, without actuating the pinion 22, after the shoe 4 has been raised as hereinbefore described. When the rack bar 31 45 moves in the direction of the arrow A, the link 46 tilts the lever 37 on its fulcrum 38, the pivotal connection 39 between the upper end of the lever and the link 40 moving to the right (Fig. 1) until the upper end of the 50 lever 37 abuts against the stop 44. The link 40 now coöperates with the arm 43 on the shaft 6 to prevent the shaft from rotating and to prevent the shoe 4 from being lowered.

When it is desired to lower the shoe 4, the operating member 45 is pulled upon, thus moving the lever 37 from the dotted line position of Fig. 1 to the solid line of that figure, the upper end of the lever moving out 55 of engagement with the stop 44, and the toggle lock afforded by the lever 37 and the link 40 being broken. The link 40 no longer restrains the shaft 6 against rotation, and the shaft may rotate, the arm 7 swinging 60 downwardly and effecting a lowering of the

shoe 4. When the lever 37 is swung from the dotted line position of Fig. 1 to the solid line position of that figure, the link 46 moves the rack bar 42 from the dotted line position to the solid line position, such an operation 70 being possible because the pinion 22 can rotate on the axle 2, it being recalled that the sleeve 18 is held retracted by the lever 12 and the cam 27. The cam 27 is now swung on its pivot 28 by means of the operating element 30, which, like the part 45, is immediately under the control of an operator. The effort of the spring 29 is overcome and the parts are restored to the position of Fig. 2, the sleeve 18 being advanced by the spring 80 100, the sleeve being no longer held retracted by the lever 12, since the cam 27 has been restored to the position shown in Fig. 2. The projection 25 on the sleeve 18 now lies in the path of the projection 26 on the hub of the pinion 22, and when the axle 2 is rotated by the ground wheel 3, the rack bar 31 will be operated, and the shoe 4 raised, as hereinbefore set forth.

The mechanism for raising the shoe by 90 the operation of the ground wheel 3, and the operation of that mechanism, have been set forth. The means for raising the shoe 4 by hand will now be described.

A segment 51 is carried by the frame of 95 the machine, a lever 52 being fulcrumed at 53 on the lower portion of the segment. The lever 52 carries a latch 54 adapted to coöperate with the notches 55 of the segment 51. The lever 52 is connected by a link 72 with 100 the arm 36 of the shaft 6. A U-shaped slide 56 is mounted for vertical reciprocation on the segment 51, the slide having elongated slots 57 receiving headed securing elements 58 mounted in the segment 51. An actuating member in the form of a bar 59 is mounted for right line reciprocation on the securing elements 58 and is held thereon, against lateral displacement by the heads of the securing elements. In the upper 110 edge of the bar 59 there are inclined notches 61 coöperating with pins 62 carried by the slide 56. A link 63 connects the bar or actuating member 59 with the extension 33 of the loop-shaped rack bar 31. 115

The lever 52 may be swung on its fulcrum 53, the link 72 rocking the shaft 6 to effect a raising or a lowering of the shoe 4 by way of the parts 7 and 8. Since the arm 36 is connected to the rack bar 31, the rack bar will be moved in the direction of the arrow A in Fig. 1, when the lever 52 is operated as above described, the rack bar and the pinion 22 in no wise interfering with the operation of the structure by hand, 120 since the pinion is free to rotate on the axle 2, saving when the sleeve 18 is advanced, as in Fig. 2, so that the projections 26 and 25 coöperate.

When the shoe 4 is raised by the action of 130

the wheel 3, the rack bar 31 moves in the direction of the arrow A. The link 63 slides the actuating member or bar 59 in the direction of the arrow A, the inclined portions 5 of the notches 61 in the bar coöperate with the pins 62 in the slide 56, the slide moves upwardly on the securing elements 58, and the crown of the slide engages the latch 54 on the lever 52 and disengages the 10 latch from the corresponding notch 55 in the segment 51. The lever 52, therefore, is free to swing responsive to the link 72 and the arm 36 when the motion for raising the shoe 4 is derived from the ground wheel 3.

15 I claim:—

1. In a grain drill, a frame; a shaft mounted to rock on the frame; a shoe; means for connecting the shoe with the shaft whereby the shoe will be raised when 20 the shaft is rotated; a ground wheel carried by the frame; means for rotating the shaft from the ground wheel; mechanism under the control of an operator for rotating the shaft; a latch restraining said mechanism; 25 and a latch-releasing device operated by the means for rotating the shaft from the ground wheel.

2. In a grain drill, a frame; a shaft mounted to rock on the frame; a shoe; 30 means for connecting the shoe with the shaft whereby the shoe will be raised when the shaft is rotated; an axle journaled on the frame; a pinion loose on the axle; a clutch connecting the axle and the pinion; 35 a rack engaging the pinion; means for connecting the rack with the shaft to rotate the shaft; and means for operating the clutch to engage it, a portion of said means lying in the path of the rack, whereby the 40 rack will actuate said means to disengage the clutch.

3. In a grain drill, a frame; a shaft mounted to rock on the frame; a shoe; means for connecting the shoe with the

shaft whereby the shoe will be raised when 45 the shaft is rotated; an axle journaled on the frame; a pinion loose on the axle; a clutch connecting the axle and the pinion; a rack engaging the pinion; means for connecting the rack with the shaft to rotate 50 the shaft; means for operating the clutch to engage it, a portion of said means lying in the path of the rack whereby the rack will actuate said means to disengage the clutch; and means operated by the rack for locking 55 the shaft against rotation after the shoe has raised.

4. In a grain drill, a frame; a shaft mounted to rock on the frame and having arms; a shoe; means for connecting the shoe with the shaft whereby the shoe will be raised when the shaft is rotated; an axle journaled on the frame; a pinion loose on the axle; a clutch connecting the pinion with the axle; a rack engaging the pinion and connected to one arm; means operated 60 by the rack for disengaging the clutch when the rack is advanced; a lever fulcrumed intermediate its ends on the arm; a link connecting one end portion of the lever with 65 the rack; a link connecting the other end portion of the lever with the other arm; means for stopping the movement of the lever when the lever swings in one direction and when the rack is advanced, thereby 70 to hold the shoe elevated; and means under the control of an operator and connected with the lever, for swinging the lever in an opposite direction, to secure a lowering of the shoe. 75

In testimony that I claim the foregoing as my own, I have hereto affixed my signature in the presence of two witnesses.

EUGENE HAGGERTY.
